(57) **CLAIM**
The ornamental design for a dispenser shroud, as shown and described.**DESCRIPTION**

FIG. 1 is an isometric view of a top, front, and left side of an ornamental design for a dispenser shroud;

FIG. 2 is a front elevational view of the dispenser shroud of FIG. 1;

FIG. 3 is a rear elevational view of the dispenser shroud of FIG. 1;

FIG. 4 is a right side elevational view of the dispenser shroud of FIG. 1;

FIG. 5 is a left side elevational view of the dispenser shroud of FIG. 1;

FIG. 6 is a top plan view of the dispenser shroud of FIG. 1; and,

FIG. 7 is a bottom plan view of the dispenser shroud of FIG. 1.

The broken lines are for the purpose of illustrating environmental structure and form no part of the claimed design.
